UNITED STATES PATENT OFFICE.

CHARLES J. PILLIOD, OF TOLEDO, OHIO, ASSIGNOR TO DANIEL SEARLES, TRUSTEE, OF TOLEDO, OHIO.

VALVE GEAR.

Application filed February 10, 1921. Serial No. 443,742.

To all whom it may concern:

Be it known that I, CHARLES J. PILLIOD, a citizen of the United States, and a resident of Toledo, in the county of Lucas and State of Ohio, have invented a certain new and useful Valve Gear; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to reverse gears, and particularly to those of the radial type for use in connection with the engine valves of locomotives.

The primary object of my invention is to provide a reverse mechanism construction which eliminates the use of the customary bell-crank-lever between the radius lever and the cross shaft of valve gears of the radial type, whereby to simplify, cheapen, lighten and otherwise improve on the construction of such gears.

The invention is fully described in the following specification, and while, in its broader aspect, it is capable of embodiment in numerous forms, a preferred embodiment thereof is illustrated in the accompanying drawings, in which,—

Figure 1 is a fragmentary side elevation of a locomotive equipped with my improved valve gear. Fig. 2 is a rear elevation of the reverse mechanism of the gear with parts in section and parts removed. Fig. 3 is a fragmentary plan view of the separate gears of the locomotive, and Fig. 4 is a side elevation of parts of the reverse mechanism of a gear in forward motion position.

Referring to the drawings, 1 designates a locomotive frame, 2 the drive wheels thereof, 3 an engine cylinder, 4 the associated cross-head operated from the piston in such cylinder, and 5 the valve stem cross-head guide for each engine.

The reverse mechanism for the valve gear, one of which is located at each side of the locomotive, is carried by a frame part 6 mounted in suitable manner on the locomotive frame, and comprises a reverse-yoke 7, journaled at the ends of its arms in the frame part 6 at 8, a radius-yoke 9 pivotally suspended from the upper end portion of

the yoke 7, with its pivot at 10, and a radius-lever 11, fulcrumed in the lower end portion of the radius-yoke 9. The lower end of the radius-lever 11 is connected by a union-rod 12 to the cross-head 4 to be operated by such cross-head, and the upper end of the radius-lever is pivotally connected to a rocker-arm 13 fixed to and projecting rearwardly from a hollow rocker-shaft 14 that extends crosswise of the locomotive and is journaled at its ends in the respective frame part 6 thereof. The opposite end of the cross-shaft 14 has a rocker-arm 15 fixedly projecting downward therefrom and connected by a radius-rod 16 to the upper end of the combination-lever 17 disposed at the opposite side of the locomotive to the operating reversing mechanism of the gear and carried by the valve stem cross-head of the associated engine, which cross-head works in the guide 5, as well understood in the art.

The radius-lever 11 of the reversing mechanism at the opposite side of the locomotive to that above described is connected at its upper end to a rocker-arm 18, which projects rearward from a cross-shaft 19 that extends through the shaft 14 and has at its opposite end a depending rocker-arm 20 in connection with the combination-lever 17 of the associated engine through a radius-rod 21. The combination-lever 17 for each engine has its lower end connected by a union-link 22 with the associated cross-head 4. It is thus evident that the combination-lever 17 receives its valve accelerating movement through the reversing mechanism from one cross-head 4, and receives its lap and lead movement through the link 22 from the other cross-head 4 at the other side of the locomotive.

The reverse-yoke 7 of each gear is connected at its upper end by a link 23 to a rocker-arm 24, one of which projects upward from the respective end of a cross-shaft 25 and the other of which projects upward from the respective end of a hollow cross-shaft 26 sleeved on the shaft 25, both shafts being suitably journaled in the frame. The shaft 25 has an arm 27 projecting upward therefrom and connected by a rod 28 to a suitable control means, and the hollow shaft 26 has a rocker arm 29 projecting downward therefrom and connected by a rod 30 to the control means. In Fig. 1

the valve gears are in neutral position and it is evident that a forward movement of the control rods 28 and 30 will impart reverse rocking movements to the shafts 25 and 26, thereby shifting one reverse yoke 7 of one gear forward and that of the other gear rearward to place the respective gears in forward running position. For backward running an opposite movement is imparted to the control rods 28 and 30, thereby effecting a reversal of the movements of the reverse yokes from that above stated.

To obtain accelerated travel of the engine valves for either forward or reverse running, the control means for the valve gears is moved forward or backward, as the case may be, and the accelerated motion is then imparted to the combination-levers 17 from the radius-levers 11 of the respective valve gears through the respective rocker-shaft and rocker-arm connections, which in one case comprises the rocker-arm 13, shaft 14, rocker-arm 15 and radius-rod 16, and in the other case comprises the rocker-arm 18, cross-shaft 19, rocker-arm 20 and radius-rod 21. The lap and lead movement of the combination-lever 17 is received from the cross-head 4 in the same manner as heretofore.

A novel feature of this invention consists in eliminating the customary bell-crank-lever from the reversing mechanism of each gear and in lieu thereof directly connecting the radius-lever to a rocker-arm on a cross-shaft, which is in turn connected by a rocker-arm and radius-rod to the respective combination-lever 17. This arrangement very materially simplifies and cheapens the construction of valve gears of the radial type and enables several parts to be eliminated.

It is evident in the operation of a valve equipped with my invention that the radius-lever 11 is rocked by the reciprocatory movements of the connected cross-head 4, the rocking movements thereof being about both the radius-yoke pivot 10 and a pivotal connection 12^a of the radius-lever therewith. The upper end of the radius-lever is connected to the respective cross-shaft of the gear and the more the reverse-yoke is shifted from neutral position the more will be the accelerated movement imparted to the cross-shaft by the movement of the radius-lever.

I wish it understood that my invention is

not limited to any specific construction, arrangement or form of the parts, as it is capable of numerous modifications and changes, without departing from the spirit of the claims.

Having thus described my invention what I claim as new, and desire to secure by Letters Patent, is,—

1. In a locomotive, the combination with an engine operated cross-head at each side and an engine valve at one side, and a combination lever connected to the engine valve and having its lower end connected to one cross-head, of a radius lever connected to and driven by the other cross-head, a cross-shaft, a rocker-arm projecting from the cross-shaft and directly connected to the upper end of the radius lever, a second rocker-arm projecting from the shaft, and means connecting said second rocker-arm and the upper end of the combination lever.

2. In a locomotive, a cross-head operated valve gear having a radius-lever, a cross-shaft, a rocker-arm connecting the cross-shaft and radius lever, a combination lever having a cross-head operated lap and lead movement and directly connected to the valve, and a connection between the cross-shaft and upper end of the combination lever for communicating valve accelerating movements thereto from radius lever actuating movements of the cross-shaft, and means for reversing the valve operating motion.

3. In a locomotive, the combination with engine operated cross-heads at both sides and an engine valve at one side of the locomotive, of a valve gear having a combination-lever connected to the valve and at one end to one cross-head, a cross-shaft having rocker-arms projecting in angular relation therefrom, a link connection between one rocker arm and the upper end of the combination-lever, a reverse-yoke mounted for rocking movements, a radius-yoke swingingly suspended from the reverse-yoke, a radius-lever carried by the radius-yoke and having one end pivotally connected to the other rocker-arm of the cross-shaft and its other end connected to and operated by the cross-head at the opposite side of the locomotive to the engine valve.

In testimony whereof, I have hereunto signed my name to this specification.

CHARLES J. PILLIOD.
